UNITED STATES PATENT OFFICE.

JOSEPH REGAN, OF ROCKVILLE, CONNECTICUT.

BRICK.

Application filed December 19, 1923. Serial No. 681,493.

To all whom it may concern:

Be it known that I, JOSEPH REGAN, a citizen of the United States, residing at Rockville, in the county of Tolland and

5 State of Connecticut, have invented new and useful Improvements in Bricks, of which the following is a specification.

This invention is a brick for the building of masonry walls and the like, and has for 10 its object to reduce the cost of manufacture and at the same time preserve all of the essential characteristics of a brick such as size, proportions, strength and durability.

The reduction in cost is accomplished by 15 omitting some of the material from each brick, and the essential characteristics of the brick are preserved by reason of the location of the omission.

In the drawings,

20 Figure 1 is a perspective view of a brick embodying the features of the present invention,

Figure 2 is a fragmentary side elevation of a wall constructed of bricks of the present invention arranged so as not to show any mortar in the joints between adjacent bricks,

25 Figure 3 is a cross sectional view on the the line 3—3 of Figure 2,

Figure 4 is a view similar to Figure 2 but 30 showing another arrangement of the bricks with mortar showing at the joints between adjacent bricks,

Figure 5 is a cross sectional view on the line 5—5 of Figure 4, and

35 Figure 6 is a top plan view of a wall portion showing the manner of using the bricks with a minimum amount of mortar.

The brick of the present invention is 40 shown in Figure 1 of the drawings wherein 1 designates the back of the brick from which rise the longitudinal side walls extending the entire length of the brick, while 45 3 designates an end wall connecting the side walls 2. It will of course be understood that the brick of the present invention is an integral rectangular brick molded in any conventional or preferred manner, and may have the usual standard dimensions or special dimensions as may be desired. The elements of the brick, which have been designated 1, 2 and 3 define a rectangular recess which has one longitudinal open side and one open end. The amount of brick material omitted is about one-third of the amount 50 of material commonly employed in the formation of a standard brick, and therefore

the cost of producing the present brick is materially less than that of a standard brick wherein the brick is continuous throughout all of its dimensions.

60 Stated in another way, the brick of the present invention is rectangular in form and is provided with a rectangular recess the cubical area of which is substantially one-third of the cubical area of the brick. The recess is disposed centrally between the side walls of the brick and has one end opening through one end of the brick, the opposite end of the recess being closed by the wall provided by the opposite end of the brick.

65 One manner of laying bricks of the present invention in a wall has been shown in Figures 2 and 3, wherein it will be seen that the bricks are placed one upon the other with the open side of the recess uppermost, the mortar designated 4 being placed within each recess so as to bond together adjacent bricks. In this arrangement, the lower 70 face of the back of one brick rests directly upon the top of the next lower brick and closes the open top of the recess therein, the open end of the recess being closed by the end wall of the adjacent brick in the same course of bricks. When the bricks are arranged in the manner shown in Figures 2 and 3, it will be noted that no mortar appears in the joints between the bricks thereby producing what is commonly called a 75 "dry wall."

80 In Figures 4 and 5 there has been shown a wall wherein the recess in each brick is at the under side thereof and the mortar 6 shows in the joints between adjacent bricks at the ends, bottoms and tops thereof. In 85 laying the bricks in this manner, mortar is placed upon the top of a brick in the usual manner, and then another brick is placed downwardly upon the mortar in the usual manner and pressed into place, a small portion of the mortar rising into each recess. In this arrangement dead air spaces are 90 formed throughout the wall.

95 In the arrangement shown in Figures 2 and 3 of the drawings the bricks eventually 100 become substantially solid bricks in that the recess in each brick is filled with mortar, and a beam may be supported upon the top of a brick at any part thereof.

105 In the arrangement shown in Figures 4 and 5 the arch shape of the brick renders it substantially as strong as a solid brick, and

a beam can be supported on the top of a brick at any portion thereof without danger of crushing the same. Furthermore, the end wall 3 of each brick is in vertical alignment 5 with the end walls of the bricks in the same vertical alignment, and therefore this portion of the wall is identical with an ordinary wall made up of bricks which are solid throughout their entire cubical areas.

10 The arrangement shown in Figure 6 is the same as that shown in Figures 2 and 3, the difference being that only a small quantity of mortar 5 is employed in each recess and at the open end thereof and against the 15 end wall of the adjacent brick.

What I claim is:

1. A building brick comprising a rectangular body having a back, opposite duplicate longitudinal side walls and an integral 20 end wall, said parts defining a rectangular recess opening through one face of the brick and through one end thereof, the inner end of the recess being closed by the end wall of the brick and the cubical area of said

space being substantially one-third of the 25 cubical area of the entire brick.

2. A building brick comprising an integral rectangular brick having a recess located centrally between the longitudinal sides of the brick, one end of the recess opening through one end of the brick and the other end of the recess terminating short of the opposite end of the brick, the cubical area of the recess being substantially one-third of the cubical area of the entire brick. 35

3. A building brick comprising a solid rectangular back, opposite duplicate longitudinal solid side walls integral with the back and extending throughout the length thereof, and a solid end wall integral with 40 the back and the side walls, the back, side and end walls defining a rectangular recess having a cubical area of substantially one third that of the entire brick, side recess opening through one end of the brick and 45 also opening through the face of the brick opposite the back thereof.

JOSEPH REGAN.
